US0D1064776S

(12) **United States Design Patent** (10) Patent No.: **US D1,064,776 S**
(45) Date of Patent: ** Mar. 4, 2025

(54) **GLUING CLAMP**

(71) Applicant: **SHENZHEN JUHE PACKAGE DESIGN CO., LTD.**, Shenzhen (CN)

(72) Inventor: **Chengyi Kuang**, Guangdong (CN)

(**) Term: **15 Years**

(21) Appl. No.: **35/518,353**

(22) Filed: **Aug. 11, 2023**

(80) **Hague Agreement Data**

Int. Filing Date: **Aug. 11, 2023**

Int. Reg. No.: **DM/231264**

Int. Reg. Date: **Aug. 11, 2023**

Int. Reg. Pub. Date: **Sep. 15, 2023**

(51) **LOC (15) Cl. 08-05**

(52) **U.S. Cl.**

USPC **D8/72**

(58) **Field of Classification Search**

USPC D8/349, 354, 355, 394, 71, 72, 395, 74

CPC B25B 5/00; B25B 5/16; B25B 5/163

See application file for complete search history.
